Primary Examiner — Darcey E Gottschalk(74) *Attorney, Agent, or Firm* — Shumaker, Loop & Kendrick, LLP; James D. Miller(57) **CLAIM**

The ornamental design for a lid, as shown and described.

DESCRIPTION

FIG. 1 is a top perspective view of an embodiment of a lid showing my new design and showing the lid in a closed position;

FIG. 2 is a bottom perspective view thereof;

FIG. 3 is a top plan view thereof;

FIG. 4 is a bottom plan view thereof;

FIG. 5 is a left side elevational view thereof;

FIG. 6 is a rear elevational view thereof;

FIG. 7 is a right side elevational view thereof;

FIG. 8 is a front elevational view thereof;

FIG. 9 is a top perspective view of the lid in an open position;

FIG. 10 is a bottom perspective view thereof; and,

FIG. 11 is a top perspective view of the lid of FIG. 1 disposed on a representative container.

The broken lines shown in FIGS. 2, 4, and 10 the drawings depict portions of the lid that form no part of the claim, and the broken lines in FIG. 11 depict a container that forms no part of the claim.

1 Claim, 4 Drawing Sheets(56)
